CLAIM

The ornamental design for an electronic device with graphical user interface, as shown and described.

DESCRIPTION

FIG. 1 is a bottom front perspective view of an electronic device showing our new design;

FIG. 2 is a bottom rear perspective view thereof;

FIG. 3 is a top front perspective view thereof;

FIG. 4 is a top rear perspective view thereof;

FIG. 5 is a front view thereof;

FIG. 6 is a rear view thereof;

FIG. 7 is a top view thereof;

FIG. 8 is a bottom view thereof;

FIG. 9 is a left side view thereof; and,

FIG. 10 is a right side view thereof.

The broken lines in the Figures show unclaimed portions of the electronic device with graphical user interface and form no part of the claimed design. The dot-dash lines in the Figures show unclaimed boundaries and form no part of the claimed design.

The Figures are illustrated to show contrasting appearance, including color. The housing of the electronic device and the graphical user interface are one appearance, and the area in between the two is another.
